UNITED STATES PATENT OFFICE.

JAMES L. STUBER, OF NEW ORLEANS, LOUISIANA.

BOX.

SPECIFICATION forming part of Letters Patent No. 264,789, dated September 19, 1882.

Application filed August 3, 1882. (No model.)

To all whom it may concern:

Be it known that I, JAMES L. STUBER, of New Orleans, in the parish of Orleans, and in the State of Louisiana, have invented certain new and useful Improvements in Boxes; and I do hereby declare that the following is a full, clear, and exact description thereof, reference being had to the accompanying drawings, and to the letters of reference marked 10 thereon, making a part of this specification.

This invention has for its objects to provide a box for various articles, which may be used to transport, store, and exhibit the same; and it is particularly designed as a sample-box, in 15 which may be packed two different kinds of articles, or two articles of the same kind but of different grades, or which may be used as an ordinary box and filled with articles of a single class or grade, as may be desired. These 20 objects I accomplish by the means illustrated in the accompanying drawings, in which—

Figure 1 represents a perspective view of my improved box opened; and Fig. 2, a longitudinal sectional view of the box, showing the 25 same closed.

In the present instance my invention is shown as applied to a cigar-box.

The letter A indicates the sides of the box, which is open at the top and bottom, and provided with hinged lids B on opposite sides, and with suitable locking or fastening devices, C, which may be of any approved description. Within the box is located a removable partition, D, which is provided with vertical end 30 pieces, E, the edges of which are flush with the open sides of the box when in place. The 35 end pieces may be dispensed with, and the partition may be provided with front and back pieces which have their edges flush with the 40 open sides of the box; or the partition may

be provided with both back and front as well as end pieces. The partition may be so arranged as to be midway between the top and bottom of the box; or it may be nearer to one than the other, and the box may be made of 45 any size to suit the requirements of the dealer. Any material may be used in the construction of the box, such as wood, paper, or the like. When required, the partition may be removed and the box employed as an ordinary box. 50

It is evident that as constructed articles of different kinds or grades may be packed in the same box and be kept separate for exhibition, and by reason of the partition being movable may be readily accessible from either 55 side, as the partition may be moved so as to bring it flush, or nearly so, with the top or bottom, whereby the articles may be conveniently removed for inspection by simply pushing them out endwise, making the box particu- 60 larly applicable for cigars.

Having thus fully described my invention, what I claim, and desire to secure by Letters Patent, is—

As a new article of manufacture, a box for 65 transporting and exhibiting various articles, consisting of a rectangular frame provided with a hinged cover at its opposite sides and a movable partition having vertical ends or sides which are flush with the sides of the 70 frame, whereby the box is divided into two compartments, substantially as shown and described.

In testimony whereof I affix my signature, in presence of two witnesses, this 18th day of 75 July, 1882.

JAMES L. STUBER.
